UNITED STATES PATENT OFFICE.

NORMAN H. SOOY, OF KANSAS CITY, MISSOURI.

PUMP-ROD SUPPORT.

Application filed August 12, 1926. Serial No. 128,903.

My invention relates to improvements in pump rod supports. It is particularly well adapted for the support of a sectional pump rod in a well casing, while the sections are being taken apart or assembled.

One of the objects of my invention is to provide a novel device for the purpose specified, which is simple, cheap, strong, durable, not liable to get out of order, which can be easily and quickly operated, which will firmly grip and support the pump rod without liability of its slipping, and at any point intermediate of the coupling ends of a section, and which eliminates one of the two elevating devices usually provided for the purpose.

A further object of my invention is to provide a novel bell nipple which will support as well as guide the pump rod in the casing.

The novel features of my invention are hereinafter fully described and claimed.

In the accompanying drawing, which illustrates my invention,

Fig. 1 is a side elevation of my preferred embodiment of my invention shown mounted in a pump casing and operatively engaged with a pump rod section, portions only of the casing and section being shown.

Fig. 2 is a vertical section on the line 2—2 of Fig. 3.

Fig. 3 is a cross section on the line 3—3 of Fig. 1.

Fig. 4 is a vertical central sectional view of a modification of my invention taken on the line 4—4 of Fig. 5.

Fig. 5 is a plan view of the form of my invention shown in Fig. 4.

Similar reference characters designate similar parts in the different views.

1 designates the usual pump casing, such as is used in gas or oil wells, having the usual discharge T joint 2, from which has been removed the usual stuffing box, and my improved bell nipple substituted therefor.

In the form of my invention shown in Figs. 1 to 3, my improved bell nipple comprises two semi-tubular co-operating members 3, detachably held together by two bolts 4 having nuts 5, and having externally threaded lower ends, adapted, when the members 3 are fastened together to form a tube, as shown, to be fitted in the internally threaded upper end of the T joint 2 in place of the stuffing box usually mounted therein, and not shown, through which ex-

tends and reciprocates the pump rod, one section 6 of which is shown extending through the bell nipple and into the pump casing 1.

For gripping the sections of the pump rod to support the same while the sections are being attached to or being detached from each other, I provide two opposing levers 7 respectively pivoted on two horizontal pins 8 respectively mounted in two pairs of lateral ears 9 with which the members 3 are respectively provided.

Said levers 7 are respectively provided with two opposing wedge jaws 10 preferably pivotedly supported at their upper ends by transverse pins 11 to the inner ends of the levers 7 respectively. The wedge jaws 10 have on their inner sides teeth 12 adapted to be forced into the pump rod sections so that the jaws will clampingly engage and support the pump rod.

The inner side of the upper ends of the bell nipple members 3 are upwardly flaring, and the outer sides of the wedge members 10 or jaws 10 are correspondingly flaring, so that, when the pump rod section 6 is moved downwardly by the weight of the pump rod, the flaring surface of the members 3 will force the jaws 10 inwardly, so as to have them tightly grip the section 6, as shown in Fig. 2.

To release the pump rod from the jaws 10, an elevating device, not shown, such as is usually employed for the purpose, is attached to the pump rod and the latter is lifted thereby, thus drawing upwardly on the wedge jaws 10, which may be swung clear of the section 6, by depressing the outer ends of the levers 7.

The nuts 5 may be removed from the bolts 4 and the bell nipple members 3 may be detached from each other and removed from the T joint 2.

This operation is reversed, when it is desired to insert the bell nipple.

If the nipple is inserted for supporting the pump rod, the parts are assembled as described, the pump rod being held suspended by the elevating device, not shown.

The jaws 10 are then inserted in the position shown in Fig. 2, after which the pump rod is slightly lowered, upon which the flaring mouth of the bell nipple members 3 will force the jaws 10 into wedging clamping engagement with the section 6 engaged thereby. The section 6 above the one so sup-

- ported may then be detached, after which the elevating mechanism is operated to lift the pump rod until the section 6 next below the one that has been engaged by the jaws 10 is in position for engagement by said jaws. The pump rod is then permitted to slightly lower until the jaws 10 engage the adjacent section 6 so as to support the pump rod.
- 10 In the modified form shown in Figs. 4 and 5, the nipple has semi-tubular members 3' provided with ears 9' and externally threaded to fit in the T joint 2. The members 3' are releasably fastened together by bolts 4' and nuts 5', as was described with reference to the nipple shown in Figs. 1 to 3.
- Levers 7' are respectively pivoted on horizontal pins 8' mounted in the ears 9'. The levers 7' at their inner ends have jaws 10' provided with teeth 12' adapted to cut into and clampingly engage the sections 6 of the pump rod. The length inwardly of the levers 7' from the pins 8' is such that when the teeth 12' engage the pump rod section 6, the levers 7' will clear the upper ends of the members 3', whereby the weight of the pump rod will cause the jaws 10' to grip

the section 6 and support it, by a wedging action, the distance between the pins 8' and the section 6 being less than the distance of the teeth 12' from said pins.

I do not limit my invention to the structures shown and described, as other modifications, within the scope of the appended claim, may be made without departing from the spirit of my invention.

What I claim is:—

In a pump rod support, a bell nipple comprising two semi-tubular members detachably connected to each other to form a tube adapted to receive therethrough a rod to be supported and having externally threaded co-operating end portions adapted to be fitted in an internally threaded end of a supporting casing, two wedge clamping members fitted in the upper end of said bell nipple and adapted to be forced inwardly thereby to a pump rod clamping position, and two levers respectively pivoted to said wedge clamping members and to said bell nipple member.

In testimony whereof I have signed my name to this specification.

NORMAN H. SOOY.
